CURTAIN ROD

Benedict E. Moriarty, Kenosha, Wis.

Application June 25, 1938, Serial No. 215,726

1 Claim. (Cl. 156—19)

This invention appertains to curtain rods, and more particularly to rods of the type used at the bottom and top edges of curtains, which are employed over the glass panes of doors and the like. 5 One general type of this rod is shown in the Letters Patent to Moller No. 1,326,951, issued January 6, 1920.

One of the primary objects of my invention is to provide an extensible curtain rod having integral supporting feet at its outer ends, provided with keyhole slots for receiving the heads of screws or nails carried by the door, sash, or sash frame, with novel means for preventing the accidental displacement of the heads from the slots. 15 Where curtain rods are provided with keyhole slots, the same can be quickly and easily attached in place, but much difficulty is encountered with the rods slipping off the heads of the fastening elements incident to the opening and closing of a 20 door or sash carrying the curtain.

In accordance with my invention, seats are provided at the narrow ends of the keyhole slots for receiving the shanks of the fastening elements, whereby movement of the rod on the fastening elements and the displacement of the rod is prevented. 25

With these and other objects in view, the invention consists in the novel construction, arrangement, and formation of parts, as will be 30 hereinafter more specifically described, claimed, and illustrated in the accompanying drawing, in which drawing:

Figure 1 is a front elevation showing a pair of my rods in use for supporting a curtain, the 35 fastening elements at the left-hand side of the rods being shown in section.

Figure 2 is a fragmentary front elevation showing one end of one rod.

Figure 3 is a fragmentary longitudinal section 40 through one rod, taken on the line 3—3 of Figure 1, looking in the direction of the arrows.

Referring to the drawing in detail, wherein similar reference characters designate corresponding parts throughout the several views, 45 the numerals 5 and 6 indicate upper and lower rods for supporting a curtain 7. The rods 5 and 6 are of identical construction, and, hence, only one will be described in detail.

Each rod includes an outer telescoping section 50 8 and an inner telescoping section 9. These sections are arranged to extensibly adjust the length

of the rod by slipping backward and forward within one another. The outer ends of the rod sections 8 and 9 have formed thereon laterally and outwardly extending attaching feet 10. These feet are adapted to fit flush against the surface to which they are to be attached, and each foot has formed therein a keyhole slot 11. The enlarged portions 11' of the slots are disposed innermost.

In use of rods of this type, the same are 10 threaded through the upper and lower hems of a curtain, and headed fastening elements 12 are driven into the member which is to carry the curtain. The heads of the fastening elements are inserted through the enlarged portions 11' 15 of the keyhole slots 11, after which the rod sections are slid outwardly, so that the shanks of the fastening elements will be disposed in the narrow portions of the keyhole slots, with the heads of the fastening elements out of alignment 20 with the enlarged portions 11' of the keyhole slots.

The rods have a tendency to work back and forth on the fastening elements, and in many instances the rods are displaced from the fastening elements. To overcome this difficulty, and in accordance with my invention, I provide notches or seats 13 in the longitudinal walls of the slots 11 at the narrow ends thereof. These notches 13 receive the shanks of the fastening elements, and the rods are held firmly against sliding movement 25 on the fastening elements. Where the curtain is slightly stretched during the placing of the rods in position, the curtain will draw the rods toward one another, so that the fastening elements will be tightly held in the seats or notches 13. 30

Changes in details may be made without departing from the spirit or the scope of my invention, but what I claim as new is:

In an extensible curtain rod, a pair of telescoping sections, flat attaching feet carried by the outer ends of said sections having key-hole slots for detachably receiving headed fastening elements, the walls of said slots at the narrow ends thereof being provided with laterally extending notches disposed at an angle to the longitudinal center of said slots receiving the shanks of the fastening elements when the rod is fastened in place and when transverse pull is exerted on the rod, whereby the fastening elements will be held out of the slots and in said notches. 45 50

BENEDICT E. MORIARTY.
